UNITED STATES PATENT OFFICE.

FALK LEWIN, OF HERZOGENBOSCH, NETHERLANDS.

MACHINE FOR PRINTING SIDE SURFACES OF METALLIC CAPSULES.

SPECIFICATION forming part of Letters Patent No. 539,276, dated May 14, 1895.

Application filed May 16, 1894. Serial No. 511,465. (No model.)

To all whom it may concern:

Be it known that I, FALK LEWIN, a subject of the Queen of Holland, residing at Herzogenbosch, in the Kingdom of Holland, have 5 invented new and useful Improvements in Machines for Printing the Side Surfaces of Metallic Capsules, of which the following is a specification.

This invention relates to a machine for producing colored impressions of letters, drawings, escutcheons, trade marks and the like on ready metallic capsules used for closing vessels, preserve-jars or as etiquettes upon mouths of bottles and the like.

15 The construction of the apparatus is shown in the accompanying drawings.

Figure 1 is a plan view of the machine; Fig. 2, a longitudinal section, and Fig. 3 a cross-section, of the same.

20 The apparatus consists essentially of three shafts *a b c* arranged one beside the other in such a manner, that, when sufficiently lengthened, they will cut each other in the same point. These shafts are supported by two

25 frames *g h* movable around vertical trunnions *l l* and capable of approaching each other or being removed from each other by means of a spindle *s*. In the frame *g* are arranged the shafts *a b* and in the frame *h* the shaft *c*.

30 The ends of the three shafts carry cones *d e f*. The cones *d* and *e* carried by the shafts *a* and *b* respectively touch each other, while the cone *f* carried by the shaft *c* can be put in or out of contact with the cone *d*.

35 The cone *f* of the shaft *c* serves to receive the metallic capsules to be imprinted. To the cone *d* of the shaft *a* is fastened a steel case having engraved into it the letters, drawings, marks, escutcheons or the like to be 40 printed on the metallic capsules. This case can of course be replaced by another one if the metallic capsules are to be provided with another drawing. The case is fastened to the cone by means of screws and nuts.

45 The cone *e* of the shaft *b* is provided with a cover of india rubber. This cone serves to transmit the color fed by a distributing apparatus *i* consisting of a series of rollers.

50 By means of this apparatus a negative printing coloring as well as a positive one may be obtained according as the case se-

cured to the cone *d* has the letters, drawings, &c., either sunken or embossed.

In Fig. 1 of the annexed drawings the case *d* has engraved into it, by way of example, a 55 escutcheon showing the letters F L. In the present case a negative printing coloring is therefore obtained.

A crank *k* applied to the median shaft *a* serves to work the apparatus.

Each of the three shafts carries toothed wheels *Z^a Z^b Z^c*, so that the movement given to the shaft *a* by the crank *k* is transmitted to each of the three shafts.

The manner of working will easily be understood from Fig. 1 of the drawings.

The apparatus works in such a manner that after the desired engraved case has been secured to the cone *d*, the frames *g* and *h* are approached to each other by means of the spindle *s* to such an extent that after a metallic capsule has been placed on the cone *d*, a contact takes place between this metallic capsule and the engraved cone *d*. The shaft *a* is then rotated by the crank *k*. The color is transmitted from the coloring cone *e* to the cone *d*, so that all the elevated parts are uniformly covered with color, while the deepened parts of the case of the cone *d* remain uncolored. The color and simultaneously with it the 70 drawings of the cone *d* are thus transferred on the metallic capsules carried by the cone *f*. In the example illustrated in the drawings the whole capsule will be colored and only the rim of the escutcheon and the letters F L will 75 remain uncolored. The color and simultaneously with it the drawings of the cone *d* are thus transferred on the metallic capsules carried by the cone *f*. In the example illustrated in the drawings the whole capsule will be colored and only the rim of the escutcheon and the letters F L will 80 remain uncolored. The color and simultaneously with it the drawings of the cone *d* are thus transferred on the metallic capsules carried by the cone *f*. In the example illustrated in the drawings the whole capsule will be colored and only the rim of the escutcheon and the letters F L will 85 remain uncolored.

Fig. 1 shows the escutcheon printed on the cone *f*. The sharpness of the printing, *i. e.*, the more or less powerful impression of the engraving on the metallic capsules can be 90 regulated by screwing suitably the spindle *s*.

In place of the cones *d e f* differently shaped rollers corresponding to the form of the capsule to be printed may be employed.

The coloring of the metallic capsules produced by means of this apparatus is, after having become dry, excessively durable and as it has been applied by pressure, it is very difficult to remove the same. The letters, escutcheons, marks, designs and the like are 95 distinguished only by their coloring and not, as the objects made according to the hitherto

used methods, by their elevation above the surface of the capsules. The letters, drawings, &c., cannot therefore be damaged in using the capsules.

- 5 The printing of the several capsules is effected very rapidly and owing to the construction of the machine a large number of capsules is manufactured within a short space of time.
- 10 The working requires an extremely small amount of force and may be effected by hand or by any suitable mechanical device.

I claim—

In a machine for producing impressions on capsules and other articles, two movable frames pivoted on independent parallel pivots, a rotatable spindle having oppositely

screw-threaded portions engaging the said movable frames, a shaft journaled in one of the frames and carrying a holder for the article which is to receive the impression and two shafts journaled in the other frame at a constant distance from each other, one of the said shafts forming a holder for an impression head, and the other shaft carrying an inking head, substantially as described.

In testimony whereof I have signed my name to this specification in the presence of two subscribing witnesses.

FALK LEWIN.
